The ornamental design for a glue brush head, as shown and described.

See application file for complete search history.

DESCRIPTION

FIG. 1 is a perspective view of a glue brush head.

FIG. 2 is a front plan view thereof.

FIG. 3 is a rear plan view thereof.

FIG. 4 is a top plan view thereof.

FIG. 5 is a bottom plan view thereof; and,

FIG. 6 is a side plan view thereof, the sides being symmetric. The broken lines and the areas within the broken lines shown in FIG. 5 illustrate portions of the glue brush head that form no part of the claimed design.
